VISE

Reginald L. Call, Meriden, Conn., assignor to The Charles Parker Company, Meriden, Conn., a corporation of Connecticut

Application May 6, 1940, Serial No. 333,585

1 Claim. (Cl. 81—33)

This invention relates to improvements in vises.

One object of this invention is to provide improved anchoring-means for the nut of a vise so that the nut will not be rocked forward toward the movable jaw, out of its properly-aligned position, when the jaws are brought together with considerable force to clamp an object.

Another object of this invention is to provide an improved anchoring construction for the nut of a vise which can be cheaply manufactured.

Another object of the invention is to provide adjustable take-up means so that the nut can be held against its stop-abutment to eliminate play or backlash of the nut.

Another object of the invention is to provide an improved vise formed of simple elements readily manufactured and readily assembled to produce an efficient durable construction at minimum cost.

With the above and other objects in view, as will appear to those skilled in the art from the present disclosure, this invention includes all features of the said disclosure which are novel over the prior art.

In the accompanying drawings forming part of the present disclosure, in which one way of carrying out the invention is shown for illustrative purposes:

Fig. 1 is a side elevation, partly in section, of a vise constructed in accordance with the present invention;

Fig. 2 is a transverse sectional view on line 2—2 of Fig. 1;

Fig. 3 is a transverse sectional view on line 3—3 of Fig. 1;

Fig. 4 is a side elevation, partly in section, of the fixed jaw of the vise, illustrating one mode of constructing the nut-way, and with the nut-way in partly-completed condition;

Fig. 5 is a rear end elevation of the fixed jaw shown in Fig. 4;

Fig. 6 is a horizontal sectional view on line 6—6 of Fig. 4, but illustrating the nut-way in completed condition;

Fig. 7 is a rear perspective view of the fixed jaw; and

Fig. 8 is a perspective view of the nut.

In the description and claim, the various parts and steps are identified by specific names for convenience, but they are intended to be as generic in their application as the prior art will permit.

In carrying out the invention in the way illustrated in the drawings, the vise includes a first

or fixed jaw-member 10 and a second or movable jaw-member 11. The fixed jaw-member 10 has a usual rectangular guide-opening 12 and a base-portion or base 13. In accordance with the present invention, a horizontal cylindrical-shape nut-way 14 is provided in the base 13 at a location adjacent the lower surface 15 of the guideway 12. The cylindrical-shape nut-way 14 can be made in any suitable way. Thus, one way 5 would be to drill a relatively-small horizontal hole of the diameter indicated by the portion of the hole 16 entirely below the lower surface 15 of the guideway 12 (as shown in Figs. 4 and 5), and then by means of a counterboring tool well known to those skilled in the art of machining, an enlarged cylindrical-shape counterbore or nut-way 14 is formed (as shown in Figs. 6 and 7). This counterboring operation causes the boring tool to cut out through the surface 15 to produce 10 the elongated side-opening 17 in the nut-way 14. Another way in which this cylindrical-shape nut-way could be made, would be to omit the original small-diameter drilling, by clamping a flat metal block (not shown) on top of the surface 15 and 15 then directly drilling or boring the nut-way 14 in the position at present shown with part of the boring or drilling operation passing through the flat block, after which the block would be discarded, all in a way well known to those skilled 20 in the art of machining. If, desired, the nut-way 25 can be finished by reaming. By having the nut-way 14 only extend a limited distance toward the movable jaw 11, a stop-abutment 18 is formed at the end of the nut-way nearest to the movable 30 or second jaw-member 11.

A nut-member or nut 19 has a shank 20 of a size to readily pass through the side-opening 17 of the nut-way 14, and has a key-portion 21 accurately formed of cylindrical shape to form a 40 secure fit with the nut-way 14.

Preferably, an adjustable form of take-up means is provided to hold the key-portion 21 against the stop-abutment 18. The particular form of adjustable take-up abutment-means illustrated in the drawings includes a cylindrical abutment-plug 22 fitting in the nut-way 14 and held therein by a drive-pin 23. A screw 24 and lock-nut 25 provide adjustable means for effectively holding the key-portion 21 against the stop-abutment 18 to prevent end-play of the nut 19.

In order to secure maximum perfection in the alignment of the finished screw-threaded hole 26 of the nut 19, the nut can be placed in its position in the fixed jaw 10 illustrated in Fig. 1

(with the main screw omitted), and by means of wedges or blocks (not shown) or otherwise, the nut can be firmly held or wedged in its desired proper position of use, and then bored in line with the hole 27 in the movable jaw 11, and later screw threading the nut hole to form the screw-threaded hole 26.

The movable jaw-member 11 is provided with a machined rectangular slide 28 to slidably fit in the rectangular guideway or slideway 12 of the fixed jaw-member 10 in a usual and well-known way. The movable jaw-member 11 has a main screw 29 rotatably mounted therein and held against longitudinal movement by means of a half-collar 30 secured to the jaw-member 11 by means of a screw 31, the half-collar 30 engaging in an annular groove 32 of the screw in a well-known way. The handle 33 serves for rotating the screw in one direction or the other to close or open the vise by the cooperative action of the screw 29 with the nut 19. In use, the cylindrical-shape of the nut-way 14 and of the key-portion 21 permits the nut 19 to swing a sufficient distance about the axis of the nut-way to permit the screw-threaded hole 26 of the nut to self-align itself with the screw 29.

Heretofore in the making of vises, the nut-way and key-portion of the nut have been made of dovetail form, but owing to the location of the abutment 18, and the cost and difficulty of machining a dovetail nut-way, it has not been commercially feasible in moderate-cost vises to make an accurate fit between the key-portion and the nut-way, with the consequence that when the jaws of the vise are heavily forced together to hold a piece of work, the nut is tilted about its engagement with the abutment 18 and toward the jaw-member 11, with the consequence of tending

to bend or distort the screw 29, thus damaging the vise.

With my improved nut-way and key-portion of cylindrical shape, however, these can be made of such very accurate fit and at such very low cost, as to enable the making of an efficient durable vise at relatively-low cost. The term "cylindrical-shape" is used for convenience as a short term to mean a nut-way or key-portion having at least two opposite cylindrical-shape side-portions such as 34 and 35, of substantial extent forming part of a cylinder. And likewise, the key-portion 21 of the nut 19 has two opposite cylindrical-shape portions 36 and 37 to effectively fit the corresponding portions 34 and 35 of the nut-way 14. And the middle of one or more of the cylindrical-shape side-portions 34 and 35 and cylindrical-shape bottom-portion 38 could be cut away or omitted without substantial harm.

The invention may be carried out in other specific ways than those herein set forth provided they do not depart from the scope of the claim.

I claim:

A vise comprising: a first jaw-member having a cylindrical-shape nut-way having a side opening of less width than the diameter of said nut-way; a screw-threaded nut having a shank-portion extending through said side opening, and a cylindrical-shape key-portion on the end of said shank-portion and fitting in said cylindrical-shape nut-way; a second jaw-member carrying a screw adapted to cooperate with said nut to force said second jaw-member relatively toward said first jaw-member; and a stop-abutment at the end of said nut-way nearest to said second jaw-member to limit the movement of said key-portion toward said second jaw-member.

REGINALD L. CALL.
